United States Patent Office.

PULASKI B. PICKENS, OF NEW YORK, N. Y.

Design No. 4,558, dated January 3, 1871.

DESIGN FOR A COLLAR-BOX COVER.

The Schedule referred to in these Letters Patent and making part of the same.

To all whom it may concern:

Be it known that I, PULASKI B. PICKENS, of the city of New York, in the county and State of New York, have invented a new and original Design for Collar-Box Cover; and I do hereby declare that the following is a full, clear, and exact description thereof, which will enable others skilled in the art to make and use the same, reference being had to the accompanying drawing forming part of this specification.

The drawing represents a perspective view of my new design for collar-box cover.

This invention relates to a new design for a collar-box cover, and consists in making the same in shape and imitation of a miniature bureau.

The box A is of oblong rectangular form, and has one face and two sides tinted or lined in imitation of the drawers and paneled or ornamented ends of a bureau, while the top *a* projects over face and sides to constitute the imitation slab.

The body B of the box is of such shape as to fit into and be concealed within the cover.

I claim as my invention—

The design for a box-cover, as shown.

P. B. PICKENS.
